INHIBITORS OF OXIDATION OF PHENOLS

Harry Clough, Norton-on-Tees, England, assignor to Imperial Chemical Industries Limited, London, England, a corporation of Great Britain

No Drawing. Application May 7, 1956
Serial No. 582,938

Claims priority, application Great Britain May 16, 1955

6 Claims. (Cl. 260—620)

This invention relates to improvements in inhibitors of the oxidation of phenols and their alkylated derivatives.

Many phenols and their alkylated derivatives are susceptible to oxidation, which usually occurs by exposure to the air, as a result of which highly-coloured compounds, and compounds having an unpleasant odour are often formed. The formation of these impurities is believed to be accelerated by the presence of metal impurities. Since the commercial value of phenols and alkylated phenols is often greatly dependent upon freedom from colour and the absence of unpleasant odour, it is important to provide means to prevent or greatly minimise the development of these deleterious features.

We have found that the oxidation of phenols and their alkylated derivatives leading to the formation of coloured compounds and/or compounds having an unpleasant odour can be inhibited by the presence of a small amount of one or more Schiff's Bases as hereinafter defined.

According to the present invention, therefore, we provide a process of inhibiting the formation by oxidation of coloured compounds and/or compounds having an unpleasant odour in phenols and their alkylated derivatives which comprises the step of adding a small amount of at least one Schiff's Base of the type hereinafter defined.

Also according to the present invention there is provided a new composition of matter which comprises at least one phenol or alkylated derivative thereof which is liable to oxidation leading to the formation of highly-coloured and/or unpleasantly odiferous compounds, and a small amount of at least one Schiff's Base of the type hereinafter defined.

By a "Schiff's Base," we mean, in this specification, a compound having the formula:

in which R comprises an aliphatic chain having the nitrogen atoms shown attached to two different carbon atoms of the aliphatic chain, and A₁ and A₂ are aromatic nuclei, or 5- or 6-membered heterocyclic nuclei having nitrogen as the heterocyclic atom or atoms, and having each OH group shown attached to a position on the nucleus A₁ or A₂ which is adjacent to the corresponding —CH=N-group. A₁ and A₂ can be identical, or different groups, and may for example be phenylene nuclei.

By a "small amount" we mean, in this specification, an amount which is at most approximately 1% by weight of the phenols or alkylated phenols with which the Schiff's Base compounds are admixed, and preferably 0.1% to 1% by weight.

It is preferred that the aliphatic chain R is a saturated aliphatic chain. A suitable saturated aliphatic chain is, for example, the ethylene radical —CH₂—CH₂—.

Suitable phenols which may be stabilised by the process of the present invention include for example monohydroxy phenols such as phenyl phenols and alkyl phenols,

2

in particular, ortho phenylphenol, para phenylphenol, and 4-methyl-2,6-di-tert. butyl phenol.

The components of the compositions of matter of the present invention may be admixed in any convenient way.

For example, they may be mixed, as in the following example, by precipitation of the phenol compounds in the presence of the Schiff's Base compounds.

It is a feature of the present invention that the inhibiting effect of the added Schiff's Base compounds persists even though the alkyl phenols to which they are added then undergo for example washing or recrystallisation treatments which might be expected to remove any of the added Schiff's Bases. These inhibitors can therefore be added to the alkyl phenols at any convenient stage, and not necessarily during the final treating steps. This is an advantage, since it may be preferable to carry out the final treating steps some considerable time after the initial production of the alkyl phenols, during which time coloured and/or unpleasantly odiferous compounds might be formed if the Schiff's Bases of the invention were not present during some part of the early stages of the preparation of the alkyl phenols.

EXAMPLE 1

25 In this example the rate of colour development is given for two samples of 4-methyl-2,6-di-tertiary butylphenol, one sample of which was treated with disalicylidene-ethylenediamine. The colour development was measured in Lovibond units according to the standard S. T. P. T. C. 30 test No. C. C. 13-50 using 1" cells, and recorded according to the formula:

$$C=Y+3R$$

35 where C=colour, Y=number of yellow units used and R=number of red units used. The samples for the present example were obtained as follows.

300 mls. of a mixture of alkylated phenols containing 70 to 75% 4-methyl-2,6-di-tertiary butylphenol was added 40 at 70° C. to a mixture of 510 mls. of methanol and 90 mls. of water and cooled for approximately one hour at 10-15° C. The precipitate which formed was substantially 4-methyl-2,6-di-tertiary butylphenol and was removed by centrifuge, dried under reduced pressure at 35 to 40° C., and stored in the dark at room temperature.

45 A second batch of 300 mls. of the alkylated phenols was treated in exactly the same way except that the methanol-water mixture also contained a quantity of disalicylidene ethylene diamine corresponding to 0.1% by weight of the alkylated phenols to be added to the methanol-water mixture.

The following table gives the colour changes observed in the two samples, stored under identical conditions and tested according to the above method.

Table 1

55	Additive	Colour of Sample		
		Weeks storage		
		0	8	12
60	Nil	1.1	3.1	5.0
65	Disalicylidene ethylenediamine	1.1	1.5	1.7

EXAMPLE 2

In this example the same procedure was adopted as described in Example 1, except that the samples were stored at 53° C. in the dark. The results for this example are given in Table 2.

Table 2

Additive	Colour of Sample				
	Days Storage				
	0	5	9	12	15
Nil	2.4	17.4	18.6	23.4	30.3
Disalicylidene ethylenediamine	1.5	1.2	1.9	2.4	4.3

EXAMPLE 3

This example shows the effect of washing the samples of 4-methyl-2,6-di-tertiary-butylphenol, which were initially precipitated and dried according to the procedure given in Example 1. Each sample was then divided equally, and one half of each sample was washed twice with its own weight of a mixture of 85% methanol and 15% water. Each sample after each wash was dried by centrifuging. All four portions of the samples were stored at 50° C. in the dark. The results of these tests are given in Table 3.

Table 3

Additive	Colour of Sample			
	Days Storage			
	0	3	16	17
Nil, sample unwashed	1.8	4.4	16.7	46.6
Nil, sample washed	1.3	2.2	6.3	18.8
SED sample unwashed	1.6	1.4	1.8	4.5
SED sample washed	1.6	1.5	2.0	3.9

SED = Disalicylidene-ethylenediamine.

I claim:

1. A composition of matter consisting essentially of a phenol which is liable to oxidative deterioration and, as a stabilizer herefore, a small amount of disalicylidene-ethylene diamine.
2. The composition of claim 1, wherein said disalicylidene-ethylene diamine is present in an amount from 0.1 to 1% by weight of said phenol.
3. A composition as claimed in claim 1 wherein said phenol is selected from the group consisting of phenyl and alkyl phenols.
4. The composition of claim 3 wherein said phenol is ortho phenyl phenol.
5. The composition of claim 3 wherein said phenol is para phenyl phenol.
- 10 6. The composition of claim 3 wherein said phenol is 4-methyl-2,6-di-tert. butylphenol.
